UNITED STATES PATENT OFFICE.

JEAN BAPTISTE PINCHARD, OF SAN FRANCISCO, CALIFORNIA.

MEANS FOR PROPELLING SHIPS, &c.

SPECIFICATION forming part of Letters Patent No. 586,390, dated July 13, 1897.

Application filed July 22, 1896. Serial No. 600,153. (No model.)

To all whom it may concern:

Be it known that I, JEAN BAPTISTE PINCHARD, a citizen of the United States, and a resident of the city and county of San Francisco, 5 in the State of California, have invented new and useful Means of Propulsion for Ships, Boats, or Vessels, of which the following is a specification.

This invention has for its object to provide 10 a substitute for the propellers hitherto employed—namely, the screw, paddle-wheel, oar, &c.—such a substitute as will greatly increase the speed of all water-craft and at the same time lessen materially the draft on the 15 propelling power.

Referring to the drawings hereunto annexed, in two sheets, for a description of my 20 said invention, Figure 1 is a diagrammatic plan showing the outline of a vessel to the sides of which my improved means of 25 propulsion have been applied. Fig. 2 is a broken elevation of one of the ship's sides, giving a face view of the propelling appliance, on an enlarged scale. Fig. 3 is a top or edge view 30 of the construction represented at Fig. 2. Fig. 4 is a cross-section on the line $x-x$, Fig. 2, looking to the right. Fig. 5 is a similar view taken from the line $y-y$ of the same, Fig. 2, the propelling apparatus being shown in an operative position.

Let A represent a steamship; B, the engine thereof; C, its boiler, and D the propeller-shaft driven by said engine. This propeller-shaft is placed transversely across the hull 35 amidships and the ends of it are projected through the ship's sides, where they are fitted in suitable bearings. Each end of said shaft carries a two-throw crank d , the outer end of which is borne by a bracket or hanger a , fastened to the ship on the outside.

The cranks d are made to reciprocate 40 winged frames, boards, or planks $E' E^2$, to which they are connected by rods $d' d^2$. These frames are set in the water edgewise by the 45 sides of the ship, where they are held and arranged to slide back and forth between rollers $e' e^2$, bearing on their top and bottom edges. Each one of said frames has a number 50 of wings or flaps $F' F^2$ connected thereto by hinges f . These hinges are made and placed in such a way that the several series of wings will close or fold under the pressure

of the water when the frames carrying them slide forward in the position represented in the left half of Figs. 1, 2, and 3, and will open 55 or spread out when said frames slide back in the opposite direction, as shown in the right half of the same figures. When open to their fullest extent, the several wings are arranged to bear against suitable stops, such as pins 60 $f' f^2$, so they may not reach out too far. Similar stops may likewise be used, if needed, to prevent them from being forced inward too far in closing. It will now be seen that when the frames $E' E^2$ are moved forward 65 upon turning the crank-shaft the wings $F' F^2$, hanging to their sides, are closed by the water and slide through it freely without splashing, as in the case of paddle-wheels and oars, &c.; but when said frames are pushed 70 back the wings hinged thereto are opened until they rest against the stops $f' f^2$, so they meet the water squarely and give the ship a powerful impulse forward.

By sliding the winged frames back and 75 forth continuously the ship is thus given a series of impulses which cause it to move ahead with more or less velocity, according to the speed at which the driving-shaft is run and the frames thereto connected are 80 reciprocated. The velocity of the ship's motion is kept uniform by having winged frames on opposite sides of the crank-shaft, so they will slide oppositely one to another, as shown, and one set will be at work while the other 85 is being pulled up for another stroke.

The arrangement above set forth operates to propel the ship forward. Now for going backward without waiting to turn the ship provision is made as follows: Extra wings or 90 flaps $F^3 F^4$ are hinged to the sides of the frames $E' E^2$ in an inverse position to that of the wings or flaps $F' F^2$, as shown in the first three views of Sheet 1 of the drawings. These additional wings are normally closed and inoperative, being kept under hooks $g^3 g^4$, formed on sliding lock-bars $G' G^2$, which carry also similar but oppositely-pointed hooks $g' g^2$, likewise adapted to close and render inoperative the wings $F' F^2$ when said additional 95 wings are brought into play. These lock-bars are held in place and guided by screws or bolts $g^5 g^6$, passing through slots $g^7 g^8$ made in them, and they are moved forward or back-

ward, as required, by sliding bolts $H' H^2$, the ends of which are outwardly bent and adapted, whenever the frames $E' E^2$ are reciprocated, to come into contact with pins $g^9 g^{10}$, placed 5 on the under side of each of the bars $G' G^2$ and projected inwardly through suitable slots in said frames. The bolts $H' H^2$ are slid to and fro by pins $h' h^2$, passed through similar slots in the sides of the ship and controlled 10 by interconnected levers H . So long as the levers H are inclined forward—that is, to the right, as represented in Figs. 2 and 3—the hooks $g^3 g^4$ lie over the wings $F^3 F^4$ and keep them closed, so they will not interfere with 15 the work of the wings $F' F^2$, the hooks $g' g^2$ being in the meanwhile away from the latter and allowing their opening and closing for the forward propulsion of the ship; but by pushing the levers H back—that is, to the left 20 from the position illustrated—the conditions are completely changed, since then the bolts $H' H^2$ force the pins $g^9 g^{10}$ back, and with them the bars $G' G^2$, as soon as the frames $E' E^2$ move forward, thereby causing the hooks 25 $g^3 g^4$ to slide away from and free the wings $F^3 F^4$ and the hooks $g' g^2$ to slide over and lock instead the wings $F' F^2$. This being done, the wings $F' F^2$ glide through the water without acting on it, while, on the contrary, the 30 wings $F^3 F^4$ do the propelling, and, as the latter are hinged and operate oppositely to the former, they of course move the ship backward, and this, it will be observed, is accomplished without reversing the engine or changing 35 the direction of rotation of the crank-shaft, so that the ship can be backed much more quickly than can be effected with other types of propellers. The wings $F^3 F^4$ rest when opened against the front side of the stops or 40 pins $f' f^2$, which are nearest to them, the same being properly bent, as at $f^3 f^4$, for the purpose. As many of these reversing or additional wings may be used as are found convenient, though for the sake of simplicity 45 only one has been represented with each wing-frame in the accompanying drawings. The bolts $H' H^2$ are so made that when the levers H are again swung forward and the frames moved back the lock-bars will also be slid 50 forward to their former position, thereby locking once more the wings $F^3 F^4$ and liberating the wings $F' F^2$, and the ship will resume its course in a forward direction.

Having described my invention, what I claim, and desire to secure by Letters Patent 55 of the United States, is—

1. In an apparatus for propelling vessels, suitable guides secured to the side of the vessel, reciprocating frames moving in said guides, and a mechanism for reciprocating 60 the frames, combined with two sets of wings, one for propelling and the other for backing the vessel, hinged to the frames; hooks for locking each set of wings in a closed position, a slide for each frame and to which the two 65 sets of hooks are secured, and means for adjusting each slide so that either set of hooks can be brought into use, substantially as set forth.

2. In an apparatus for propelling vessels, 70 suitable guides secured to the side of the vessel, a sliding frame moving in the guides, and two sets of wings which operate in opposite directions, combined with an endwise-moving slide carrying hooks for each set of wings, 75 an operating mechanism for moving the slides, located inside of the vessel, and connecting with the slides through the sides of the vessel, substantially as specified.

3. In an apparatus for propelling vessels, 80 a sliding frame, provided with stops $f' f^2 f^3 f^4$, two sets of hinged wings F' , F^2 , F^3 , F^4 , which operate in opposite directions; and two sets of hooks, turned in opposite directions, for locking either set of wings in a closed position, combined with slides to which the hooks are secured; the pins projecting from the inner sides of the slides, the sliding bolts having outwardly-turned ends, and the levers H , and pins h' , h^2 for reciprocating the bolts, 85 substantially as shown.

4. In a propelling apparatus the combination of a slidable frame having two sets of oppositely-hinged wings, a locking-bar provided with oppositely-pointed hooks arranged to 95 slide respectively and alternately over one set of said wings and lock the same, a lever, and suitable connections whereby said lever is made to shift said bar and said hooks, substantially as described.

In testimony whereof I affix my signature in presence of two subscribing witnesses.

J. B. PINCHARD.
